(57) **CLAIM**

An ornamental design for a connector for wearable electrode connector assembly for ECG monitoring, as shown and described.

DESCRIPTION

FIG. 1 is a perspective view showing the new design;
FIG. 2 is a front plan view thereof;
FIG. 3 is a rear plan view thereof;
FIG. 4 is a left side elevational view thereof;
FIG. 5 is a right side elevational view thereof;
FIG. 6 is a top view thereof;
FIG. 7 is a bottom view thereof;
FIG. 8 is a perspective view showing a second embodiment of the new design;
FIG. 9 is a front plan view thereof;
FIG. 10 is a rear plan view thereof;
FIG. 11 is a left side elevational view thereof;
FIG. 12 is a right side elevational view thereof;
FIG. 13 is a top view thereof; and,
FIG. 14 is a bottom view thereof.
